ROPE HAULAGE APPARATUS FOR MINES

John Bridie Mavor, Glasgow, Scotland, assignor
to Mavor & Coulson, Limited, Glasgow, Scot-
landApplication April 8, 1948, Serial No. 19,796
In Great Britain October 10, 1946

4 Claims. (Cl. 262—1)

1

This invention relates to rope haulage apparatus for mines, say coal mines, and its object is to provide an improved anchorage for a haulage rope or other cable.

According to the invention a haulage anchorage comprises a hydraulic unit including a jack component which presses against the mine floor and roof and a haulage component which is subjected to hydraulic pressure by the pull of a haulage cable and transmits the pressure to the jack component so as to augment the anchoring force exercised thereby. That is to say, the augmented anchoring force exercised by the jack is proportionate to the pull applied to the haulage cable.

Preferably, hydraulic cylinders incorporated in the components of the anchorage are so designed that the force exercised by the jack is several times as great as the haulage pull applied to the cable.

Examples illustrative of the invention are shown by the accompanying diagrammatic drawing, in which:

Fig. 1 is a sectional elevation of a haulage rope anchorage having a two-cylinder jack component, the section being on the line 1—1 of Fig. 2, which is a sectional elevation on the line 2—2 of Fig. 1.

Fig. 3 is a sectional elevation of a haulage rope anchorage having a one-cylinder jack component, the section being on the line 3—3 of Fig. 4, which is a sectional elevation on the line 4—4 of Fig. 3.

Referring to Figs. 1 and 2, in this example, the jack component of the improved anchorage consists of two juxtaposed hydraulic cylinders 5 and 6 having a common base 4 which bears upon the floor A of a mine and rams 7 and 8 whose heads 9 are formed to bear upon its roofwork B. The cylinders 5 and 6 are interconnected by a strong cross-connection 10 including a horizontal hydraulic cylinder 11. The cylinder 11 is closed at one end 12 and the rod 3 of its ram extends through a gland 14 at the other end. The gland end of this cylinder 11 opens through ports 15 into both jack cylinders 5 and 6. A haulage rope 16 is attached to the rod 13. The pistons of the three rams 7, 8 and 13 are indicated by 17, 18 and 19 respectively.

The anchorage includes a motor-driven hydraulic pump 20 for supplying hydraulic liquid through a conduit 21 with a stop valve 22 to the cylinders 5, 6 and 11. The arrangement is such that, when the valve 19 is opened and the pump 17 is operated, the hydraulic liquid pumped into the cylinders 5, 6 and 11 performs these actions, namely: the pistons 17 and 18 are forced up so

as to extend the jacks, which therefore anchor themselves between the floor A and roof B; the piston 19 is forced to the closed end 12 of its cylinder 11. Thereafter the pump 20 is stopped and the valve 22 is closed, so that the hydraulic liquid is locked inside the unit composed of the intercommunicating cylinders 5, 6 and 11. Thus when the rope 16 is pulled, the hydraulic liquid in the horizontal cylinder 11 is subjected to augmented pressure and the hydraulic fluid in the remainder of the unit, namely the jack cylinders 5 and 6, is subjected to the same pressure, so that the anchoring hold applied between the floor A and roof B by the jacks is also augmented.

15 The effective areas of the pistons 17, 18 and 19 of the rams 7, 8 and 13, respectively, are so proportioned that the jacks apply equal anchoring forces which total an amount several times as great as the force applied to the horizontal ram 13 by the pull of the rope 16.

In the simpler construction according to Figs. 3 and 4, only a single cylinder 5 and ram 7 are provided as the jack component. The cylinder 11 of the haulage-rope ram 13, 19 opens through a port 15 into the single cylinder 5; and it is into the bottom of this cylinder 5 that the supply conduit 21 from the pump 20 opens. In other respects, the construction is similar to that already described with reference to Figs. 1 and 2, the same numerals being used to denote corresponding parts. It will be noted that the jack piston 17 is substantially larger in effective area than the haulage piston 19, so that the anchorage force will be proportionately greater than the haulage force.

I claim:

1. A mine haulage anchorage comprising a hydraulic cylinder-and-ram anchoring component for use as a jack to press against the mine floor and roof, a hydraulic haulage component parts of which consist of a cylinder and a ram, one of the parts being movable relative to the other thereof under the pull of a haulage cable, and a connection for hydraulic liquid between the cylinders of said components, so that a pull applied to said one of the parts augments the hydraulic pressure in the haulage component and the augmented pressure is transmitted to the anchoring component.

2. A mine haulage anchorage as claimed by claim 1 in which the respective components inter-communicate so that each of them is subjected to the same hydraulic pressure and in which the respective components are so proportioned that

3

the anchoring force is greater than the force of the haulage pull.

3. A mine haulage anchorage comprising a jack component which when extended engages the mine floor and roof, said jack including a hydraulic cylinder, in combination with a haulage component consisting of a hydraulic cylinder and a ram movable therein, the ram being attachable to a haulage cable to receive the pull thereof, and a connection to pass hydraulic liquid from the haulage-component cylinder to the jack-component cylinder in order to increase the jacking pressure with increase in the pull of said cable.

4. A mine haulage anchorage as claimed by claim 3 in which the jack component includes a

10

15

4

plurality of hydraulic cylinders which have effective areas totalling substantially more than the effective area of the haulage-component cylinder, each of said cylinders having the said hydraulic-liquid connection with the haulage-component cylinder.
